(57) **CLAIM**

The ornamental design for a cell counting plate as shown and described.

DESCRIPTION

1. Cell counting plate

1.1 : Front

1.2 : Back

1.3 : Left

1.4 : Right

1.5 : Top

1.6 : Bottom

1.7 : Perspective view 1

1.8 : Perspective view 2

1.9 : Enlarged view of Section A in view 1.5

1.10 : Enlarged view of Section B in view 1.7

The name of this design product: Cell counting plate; purpose of the product with this design: for counting cells; the main points of the design of the product are the shape of the product; the picture or photo that best shows the main points of the design: reproduction 1.7 (perspective view); this design product is made of transparent material, the curve

(Continued)

lines and the label “A”, “B” in reproductions **1.5**, **1.7** are for the purpose of depicting the cut line of the enlarged view and form no part of the claim.

The dash dot dash broken lines in **1.9** and **1.10** represent the bounds of the enlargement taken from **1.5** and **1.7** and forms no part of the claimed design.

1 Claim, 10 Drawing Sheets
